(57) **CLAIM**

I claim the ornamental design for a placket for a dress shirt, as shown and described.

DESCRIPTION

FIG. 1 is a front elevational view of the placket for a dress shirt showing my new design; and,

FIG. 2 is an enlarged fragmentary front elevational view of the placket in the circular broken line of FIG. 1.

The circular broken line shown in FIG. 1 and 2 represent boundary lines.

The broken lines on the collar of the shirt represent stitching.

The broken line showing of a tie in FIG. 1 is included for the purpose of illustrating environmental structure and forms no part of the claimed design.
